(57) **CLAIM**

The ornamental design for a wearable breast pump, as shown and described.

DESCRIPTION

FIG. 1 is a front perspective view of the wearable breast pump according to the present design;

FIG. 2 is a front elevation view of the wearable breast pump of FIG. 1;

FIG. 3 is a rear elevation view of the wearable breast pump of FIG. 1;

FIG. 4 is a right-side elevation view of the wearable breast pump of FIG. 1;

FIG. 5 is a left-side elevation view of the wearable breast pump of FIG. 1;

FIG. 6 is a top plan view of the wearable breast pump of FIG. 1; and,

FIG. 7 is a bottom plan view of the wearable breast pump of FIG. 1.

The equal-length broken lines in the drawings depict portions of the wearable breast pump that form no part of the claimed design.

1 Claim, 7 Drawing Sheets
